UNITED STATES PATENT OFFICE.

ADOLF BARSTAD, OF SMILEY TOWNSHIP, PENNINGTON COUNTY, MINNESOTA.

CONCRETE WALL MOLD.

Application filed October 6, 1925. Serial No. 60,864.

To all whom it may concern:

Be it known that I, ADOLF BARSTAD, a citizen of the United States, residing at the township of Smiley, in the county of 5 Pennington and State of Minnesota, have invented certain new and useful Improvements in a Concrete Wall Mold, of which the following is a specification.

This invention relates to improvements in 10 molds and more particularly for a mold used in forming a concrete wall.

One of the important objects of the present invention is to provide a mold which may be readily set up in position for use, the 15 same including inner and outer forms whereby the concrete wall which is to be formed is provided with an air duct between the walls.

A further object is to provide a mold 20 of the above mentioned character which includes a simple and efficient means for joining the spaced walls together at certain intervals whereby the air ducts will be formed between the inner and outer portions of the 25 walls.

A still further object is to provide a mold of the above mentioned character which includes an adjustable outer section whereby 30 the sections of the wall and the portions thereof between the air duct in the outer faces to be regulated.

A further object is to provide a mold of the above mentioned character which is simple in construction, inexpensive, and furthermore adapted to the purposes for which 35 the same is designated.

Other objects and advantages of this invention will become apparent during the course of the following description.

40 In the accompanying drawing forming part of this specification and in which like numerals are employed to designate like parts throughout the same:

Figure 1 is a top plan view of the mold 45 embodying my invention showing the same in its assembled position.

Fig. 2 is a sectional view taken approximately on line 2—2 of Fig. 1.

Fig. 3 is a side elevation of one of the 50 outer forms or sections and the supporting members associated therewith.

Fig. 4 is a fragmentary side elevation of the inner forms or sections showing the position of the inverted U-shaped member which 55 provides the connection between the inner and outer portions of the wall.

Fig. 5 is a detail perspective view of the aforementioned U-shaped member, and

Fig. 6 is a detail perspective view of the locking plate.

In the drawings wherein for the purpose of illustration is shown the preferred embodiment of my invention, the numeral 1 designates the outside form, the same being substantially of rectangular design. Cooperating with the outside forms are the inside forms 2, the same being also substantially rectangular in design. Each of the forms comprises a single piece of wood or metal and arranged on the outer face of each of the outer forms are the strips 3.

The supporting means for the outer forms comprises a pair of standards 4 and 5 respectively, the same being of a suitable length.

A pair of transversely extending spaced 75 cross bars 6 and 7 respectively, are secured on opposite sides of the standards 4 and 5 adjacent the upper ends thereof by the fastening means illustrated at 8. The purpose of the spaced cross bars will be presently 80 apparent. A bolt 9 is threaded transversely through the lower end of each of the standards and engages the lower strip 3 on the outside of each of the outer forms 1 for the purpose of moving the same inwardly towards each other. Vertically extending bolts 85

10 are threaded into the upper edges of the upper strip arranged on the outer face of each of the outer forms 1 and these bolts extend upwardly between the spaced cross 90 bars 6 and through the blocks 11 which are adapted for slidable movement across the upper edges of the spaced cross bars so as to permit the upper portions of the outer forms to be moved inwardly towards each 95 other and held in the desired adjusted position.

Vertically extending bolts 10 are threaded into the upper edges of the upper strip arranged on the outer face of each of the outer forms 1 and these bolts extend upwardly between the spaced cross 90 bars 6 and through the blocks 11 which are adapted for slidable movement across the upper edges of the spaced cross bars so as to permit the upper portions of the outer forms to be moved inwardly towards each 95 other and held in the desired adjusted position so that various thicknesses of the wall which is to be formed may be regulated. The upper ends of the spaced standards are held in proper spaced relation with respect 100 to each other through the medium of the transversely extending members 12.

The inner forms or sections 2 are provided in their inner opposed faces adjacent the upper edges thereof with the arcuate 105 grooves 13 for receiving the curved ends 14 of the locking plates 15 which are supported on the threaded rods 16, the latter extending upwardly between the spaced inner forms, an actuating handle 17 being 110 provided at the upper end of the threaded rods 16 while the lower end is connected to

the respective lower edges of the inner forms by the toggle joints designated generally by the numeral 18.

As is clearly illustrated in Figs. 2 and 4 of the drawings, the inner sections or forms are of such height as to necessitate the placing of the sections comprising the inner forms in superposed relation so that the lower edge of the upper sections will rest on the upper edge of the lower sections and said sections will be disposed in the same vertical plane. The upper section is of greater length than the lower section and the lower sections are spaced from each other for accommodating the substantially inverted U-shaped member 19, the purpose of which is to provide a means whereby a connection between the inner and outer sides of the wall may be had when a wall is to be formed by the mold with the same being provided with an air duct.

The use of these molds may be briefly stated as follows. After the foundation for the wall has been formed, the parts comprising my improved mold are assembled in the manner as shown in Fig. 2 and the concrete or other material from which the wall to be formed is placed between the inner and outer forms of the mold and the usual tamping process is employed. In constructing a straight wall, enough of the forms are provided to accommodate the length of the wall. It is of course to be understood that the form may also be used in constructing walls for silos, towers or other buildings and the shape of the forms will necessarily correspond with the structure which is to be formed. By rotating the threaded rods 16 in one direction, the locking plates 15 are brought into engagement with the arcuate grooves 13 provided for the curved ends of the plate in the interposed faces of the inner forms and furthermore the toggle joints 18 are spread apart for holding the lower portions of the inner forms in proper spaced relation with respect to each other.

The bolts 9 and 10 will secure the outer forms in proper spaced relation with respect to the adjacent inner forms so that the desired thickness of the inner and outer portions of the wall which is to be constructed may be obtained.

For the purpose of preventing the collapsing of the inner forms, there is provided the coiled springs 20, the same being disposed between the inner opposed faces of the inner forms adjacent the upper edges thereof.

After the concrete has been set, the forms are removed as is also the inverted U-shaped member 19 and the parts are again assembled so as to build up the wall and at spaced intervals. The inverted U-shaped member 19 is used for forming a connection between the inner and outer portions 21 and 22 respec-

tively of the concrete wall at spaced intervals whereby an air duct 23 is formed between the inner and outer portions of the concrete wall for permitting the circulation of air through the wall for the purposes well known in the art.

It is of course to be understood that the open end bottom of the inverted U-shaped member 19 is to be closed when forming the joint between the inner and outer portions of the concrete wall so as to prevent the material from escaping and when the concrete has firmly set, the parts may be readily and easily removed.

The inverted U-shaped member 19 is inserted between the adjacent end of the sections of the inner forms, the open bottom of the aforementioned member being temporarily closed when the concrete is poured and until the same hardens. This U-shaped member is inserted in such a manner as to have its open sides disposed adjacent the respective concrete walls which are to be formed.

When the concrete is poured into the mold between the inner and outer forms, the same will flow into the inside of the U-shaped member through the open sides thereof where the U-shaped member will be filled, thus forming a union or connection between the inner and outer walls. The poured concrete will be prevented from escaping through the open bottom of the U-shaped member by reason of a closure provided therefor. Any suitable means may be employed for closing the open bottom of the inverted U-shaped member such as the use of a piece of wire mesh screen or a metallic plate which is placed across the top of the portions of the concrete walls already formed and on which the mold is placed, the lower free edges of the arms of the inverted U-shaped member resting on said screen or plate. It will of course be understood that the wire mesh screen or plate whichever is used will remain embedded in the concrete after the latter has hardened, and the forms and the U-shaped member have been removed.

The provision of a mold of the above mentioned character will enable a concrete wall with an air space therein to be formed in a manner which is simple and efficient and at a very low cost, the parts comprising a mold being readily assembled or disassembled and furthermore adjustable.

While I have shown the preferred embodiment of my invention, it is to be understood that various changes in the size, shape and arrangement of parts may be resorted to without departing from the spirit of sacrificing any of the advantages of the appended claims.

Having thus described my invention, what I claim as new is:—

1. A mold for forming a concrete wall with an air duct comprising outer and inner forms, means for securing the outer forms, means for locking the inner forms in their assembled position, and means associated with the inner forms for forming a connection between the portions of the walls formed by the aforementioned forms.
2. A mold for forming a concrete wall with an air duct comprising outer and inner forms, means for securing the outer forms, means for locking the inner forms in their assembled position comprising a vertically disposed threaded rod, a toggle joint connecting the lower end of the rod with the respective lower ends of the inner forms, and a locking plate carried by the upper portion of the rod and adapted to be brought into locked engagement with the inner opposed faces of the inner forms adjacent the upper edges thereof.
3. A mold for forming a concrete wall with an air duct comprising outer and inner forms, means for securing and supporting the outer forms, means for locking the inner forms in their assembled positions, additional means for adjusting the outer forms with respect to the inner forms, the inner forms including spaced sections, and a substantially inverted U-shaped member adapted to be disposed between the spaced ends of the sections whereby a joint between the inner and outer portions of the concrete wall to be formed is provided.
4. A mold for forming a concrete wall with an air duct, comprising inner and outer forms, supporting means for the outer forms, comprising spaced vertical standards, a pair of spaced cross bars extending transversely between the upper portions of the standard and secured thereto, bolts threaded transversely through the lower ends of the standards and engaging the adjacent portions of the outer forms, bolts extending vertically between the cross bars and threaded into the upper portions of the outer forms, blocks slideable on the cross bars and through which the last mentioned bolts extend, said bolts providing a means for adjusting the outer forms with respect to the inner forms, means for locking the inner forms in their assembled position.
5. A mold for forming a concrete wall with an air duct, comprising inner and outer forms, supporting means for the outer forms, comprising spaced vertical standards, a pair of spaced cross bars extending transversely between the upper portions of the standard and secured thereto, bolts threaded transversely through the lower ends of the standards and engaging the adjacent portions of the outer forms, bolts extending vertically between the cross bars and threaded into the upper portions of the outer forms, blocks slideable on the cross bars, and through which the last mentioned bolts extend, said bolts providing a means for adjusting the outer forms with respect to the inner forms, means for locking the inner forms in their assembled position, said means comprising a vertically disposed threaded rod, a toggle joint connecting the lower end thereof with the lower ends of the respective inner forms, the inner opposed faces of the upper portions of the inner forms being provided with arcuate grooves, and a locking plate carried by the upper portion of the threaded rod, the ends being curved and adapted for cooperation with the arcuate grooves when the plates are disposed in a predetermined position.

In testimony whereof I affix my signature.

ADOLF BARSTAD.
